UNITED STATES PATENT OFFICE

GUSTAVE ALPHONSE MARIE LAMBLIN-PARENT, OF LILLE, FRANCE

DESIGN FOR A COVER GLASS LENS FOR HEADLIGHTS

Application filed December 1, 1930. Serial No. 37,843. Term of patent 7 years.

To all whom it may concern:

Be it known that I, GUSTAVE A. M. LAMBLIN-PARENT, a citizen of the Republic of France, residing at Lille, in the Department of Norde, France, have invented a new, original, and ornamental Design for a Cover Glass Lens for Headlights, of which the following is a specification, reference being had to the accompanying drawing, forming part hereof.

Figure 1 is a vertical sectional view of a cover glass lens, showing my new design.

Figure 2 is a front face view thereof.

Figure 3 is a perspective view from the

rear at an angle, of the section shown in Figure 1.

Figure 4 is a rear view in perspective, the top edge of the cover glass being tilted toward the observer.

Figure 5 is a horizontal sectional view along the broken line of Figure 2.

I claim,—

The ornamental design for a cover glass lens for headlights, substantially as shown.

In witness whereof I have hereunto set my hand.

GUSTAVE ALPHONSE MARIE LAMBLIN-PARENT.
